R. L. HILL,

PROCESS OF PRODUCING AROMATIC HYDROCARBONS.
APPLICATION FILED JULY 26, 1915. RENEWED MAR. 28, 1916.

1,269,439.

Patented June 11, 1918.

By his Attorney, Inventor
Roy L. Still, Prud' Highsmith.

UNITED STATES PATENT OFFICE.

ROY LINDEN HILL, OF CHESTER, PENNSYLVANIA, ASSIGNOR TO E. I. DU PONT DE NEMOURS POWDER COMPANY, OF WILMINGTON, DELAWARE, A CORPORATION OF NEW JERSEY.

PROCESS OF PRODUCING AROMATIC HYDROCARBONS.

1,269,439.

Specification of Letters Patent. Patented June 11, 1918.

Application filed July 26, 1915, Serial No. 41,888. Renewed March 28, 1918. Serial No. 225,870.

To all whom it may concern:

Be it known that I, Roy LINDEN HILL, of Chester, in the county of Delaware, and in the State of Pennsylvania, have invented 5 a certain new and useful Improvement in Processes of Producing Aromatic Hydrocarbons, and do hereby declare that the following is a full, clear, and exact description thereof.

10 My invention relates generally to the production of low boiling aromatic hydrocarbons from mixtures of higher boiling aromatic compounds, but it is especially applicable to the production of benzol and toluol 15 from solvent naphtha or heavy naphtha.

It has been before known that when such mixtures are passed through tubes maintained at a high temperature, either at atmospheric or a higher pressure, decomposition 20 takes place so that the condensate when obtained contains a certain percentage of benzol and toluol.

The object of my invention is to increase the percentage of low boiling aromatic hydrocarbons, as for example, benzol and toluol, in processes of the above character.

In general, my invention relates to a process in which in the heated tubes, through which the higher boiling aromatic compounds 30 are passed, there is provided a body of a carbid, such for example as barium carbid or calcium carbid. This results in an increased production of benzol and toluol in the condensate obtained.

35 While my invention may be carried out in connection with many different forms of apparatus, for the purpose of illustration, I have shown only one form of apparatus in the accompanying drawings, in which,

40 The figure is a diagrammatic side elevation of an apparatus which may be used for carrying out my invention.

In the drawings I have shown a container 1, which is adapted to be supplied with a body of a higher boiling aromatic hydrocarbon, such for example as solvent naphtha or heavy naphtha through a funnel 2 attached to the container 1 and having a hand-valve 3. The container 1 is provided 45 with an outlet pipe 4, leading into a tube 5,

said pipe 4 having a hand-valve 6. Said container 1 is, furthermore, provided with an air pressure supply pipe 7 having a hand-valve 8, and a vent pipe 9 provided with a valve 10, and an equalizer pipe 11 having a valve 12. The tube 5 is preferably provided with a body of a carbid 13, which may for example be barium carbid or calcium carbid, which is distributed along the bottom of the tube 5 and is arranged to pass through a furnace 14, which may be heated in any desired manner. The outlet end of the tube 5 is connected to a coil 15 of a condenser 16, said coil 15 having at its inlet end a hand-valve 17, and at its outlet end a hand-valve 18. The container 1 is preferably provided with a liquid gage 19.

In the operation of my process, a body of solvent naphtha or heavy naphtha is fed into the container 1 through the funnel 2, the valves 3 and 10 being open but the valves 6, 8 and 12 being closed. When the feeding of the naphtha into the container 1 has been completed the valves 3 and 10 are closed and the body of material in the container is fed outwardly through the pipe 4 by opening the valves 6 and 8 and applying air pressure to the body of liquid in the container 1, if desired, through the pipe 7, or by opening the valve 12 in the equalizer pipe 11, with valve 8 closed, thus dispensing with air pressure. As soon as the naphtha reaches the tube 5, which is preferably maintained above 500° C., and the most suitable temperature of which is 600° C., it is volatilized and it then passes through the tube 5 in the form of vapor over the body of the carbid 13. The pressure within the tube 5 may be controlled, and is preferably maintained above the atmospheric pressure by the valve 17. The vapor thus produced, as it passes out of the tube 5, is conducted to the condensing coil 15, the pressure in which is controlled by the valve 18. A condensate is thus obtained at the outlet end of the coil 15 which contains benzol and toluol in larger percentages than previously obtainable in processes of this type.

While I have described my invention above in detail, it is to be understood that

many of the details of the process given above may be varied without departing from the spirit of my invention. For example, the method of introducing the naphtha and 5 of condensing the gases may be varied as desired, and the same is true of the kind of apparatus used, particularly the size and shape of the tube, and the means used for heating the same.

10 I claim:—

1. The process which comprises heating an aromatic hydrocarbon in the presence of an alkaline earth metal carbid, so as to produce a lower boiling hydrocarbon.

15 2. The process which comprises heating an aromatic hydrocarbon having a higher boiling point than toluol, in the presence of an alkaline earth metal carbid so as to produce a lower boiling hydrocarbon.

20 3. The process which comprises heating heavy naphtha in the presence of an alkaline earth metal carbid, so as to produce a lower boiling hydrocarbon.

25 4. The process which comprises heating an aromatic hydrocarbon in the presence of calcium carbid, so as to produce a lower boiling hydrocarbon.

30 5. The process which comprises heating an aromatic hydrocarbon having a higher boiling point than toluol, in the presence of calcium carbid so as to produce a lower boiling hydrocarbon.

35 6. The process which comprises heating heavy naphtha in the presence of calcium carbid, so as to produce a lower boiling hydrocarbon.

40 7. The process which comprises heating to above 500° C. an aromatic hydrocarbon in the presence of an alkaline earth metal carbid, so as to produce a lower boiling hydrocarbon.

45 8. The process which comprises heating to above 500° C. an aromatic hydrocarbon, having a higher boiling point than toluol, in the presence of an alkaline earth metal carbid so as to produce a lower boiling hydrocarbon.

50 9. The process which comprises heating to above 500° C. heavy naphtha in the presence of an alkaline earth metal carbid, so as to produce a lower boiling hydrocarbon.

55 10. The process which comprises heating to above 500° C. an aromatic hydrocarbon in the presence of calcium carbid, so as to produce a lower boiling hydrocarbon.

60 11. The process which comprises heating to above 500° C. an aromatic hydrocarbon, having a higher boiling point than toluol, in the presence of calcium carbid so as to produce a lower boiling hydrocarbon.

65 12. The process which comprises heating to above 500° C. heavy naphtha in the presence of calcium carbid, so as to produce a lower boiling hydrocarbon.

13. The process which comprises heating, 65 at a pressure greater than the atmospheric pressure, an aromatic hydrocarbon in the presence of an alkaline earth metal carbid, so as to produce a lower boiling hydrocarbon.

70 14. The process which comprises heating, at a pressure greater than the atmospheric pressure, an aromatic hydrocarbon, having a higher boiling point than toluol, in the presence of an alkaline earth metal carbid 75 so as to produce a lower boiling hydrocarbon.

15. The process which comprises heating, at a pressure greater than the atmospheric pressure, heavy naphtha in the presence of 80 an alkaline earth metal carbid, so as to produce a lower boiling hydrocarbon.

16. The process which comprises heating, at a pressure greater than the atmospheric pressure, an aromatic hydrocarbon in the 85 presence of calcium carbid, so as to produce a lower boiling hydrocarbon.

17. The process which comprises heating, at a pressure greater than the atmospheric pressure, an aromatic hydrocarbon, having 90 a higher boiling point than toluol, in the presence of calcium carbid so as to produce a lower boiling hydrocarbon.

18. The process which comprises heating, at a pressure greater than the atmospheric 95 pressure, heavy naphtha in the presence of calcium carbid, so as to produce a lower boiling hydrocarbon.

19. The process which comprises heating to above 500° C. at a pressure greater than 100 the atmospheric pressure, an aromatic hydrocarbon in the presence of an alkaline earth metal carbid, so as to produce a lower boiling hydrocarbon.

20. The process which comprises heating to above 500° C., at a pressure greater than the atmospheric pressure, an aromatic hydrocarbon, having a higher boiling point than toluol, in the presence of an alkaline earth metal carbid so as to produce a lower 110 boiling hydrocarbon.

21. The process which comprises heating to above 500° C., at a pressure greater than the atmospheric pressure, heavy naphtha in the presence of an alkaline earth metal carbid, so as to produce a lower boiling hydrocarbon.

22. The process which comprises heating to above 500° C. at a pressure greater than the atmospheric pressure, an aromatic hydrocarbon in the presence of calcium carbid, so as to produce a lower boiling hydrocarbon.

23. The process which comprises heating to above 500° C., at a pressure greater than the atmospheric pressure, an aromatic hydrocarbon, having a higher boiling point than toluol, in the presence of calcium carbid

so as to produce a lower boiling hydrocarbon.

24. The process which comprises heating to above 500° C., at a pressure greater than 5 the atmospheric pressure, heavy naphtha in the presence of calcium carbide, so as to produce a lower boiling hydrocarbon.

In testimony that I claim the foregoing I have hereunto set my hand.

ROY LINDEN HILL.
